UNITED STATES PATENT OFFICE.

JOHN EDWARD NACE, OF HANOVER, PENNSYLVANIA.

SPOOL-BEARING.

1,068,264.

Specification of Letters Patent.

Patented July 22, 1913.

Application filed June 20, 1912. Serial No. 704,813.

To all whom it may concern:

Be it known that I, JOHN E. NACE, a citizen of the United States, and a resident of Hanover, in the county of York and State of Pennsylvania, have invented a new and Improved Spool-Bearing, of which the following is a full, clear, and exact description.

My invention relates more particularly to means for supporting spools in cabinets adapted to display lace and insertion.

The invention will be particularly described in connection with the specific description hereinafter to be given.

Reference is to be had to the accompanying drawings forming a part of this specification, in which similar characters of reference indicate corresponding parts in all the views.

Figure 1 is an elevation, partly in section, of a spool and supporting standards having bearings formed in accordance with my invention. Fig. 2 is a cross section on about the line 3—3 of Fig. 1; and Fig. 3 is a view 25 of the blank form which the bearings of the spool are formed.

The spool, in the form shown, consists of a spindle 26 and disks or heads 27. Each end of the spindle has a bearing in a hanger 30 socket 35, which is formed from a blank, as shown in Fig. 3, said blank presenting an elongated body with spurs or points 36 at each end, the base of the said spurs being narrower than the total width of the strip 35.

The blank is bent into curved form, as shown clearly in Fig. 2, and is folded on the transverse line 37, at right angles to the length of the strip, and then folded on the

diagonal line 38 at the base of the spurs 36. By thus folding the blank, the spurs 36 are folded down onto the end of the blank, and a member 39 at the base of the spur folds down onto the body of the strip, with the spurs between said member and the body of the strip, the said spurs, 36, assuming positions projecting beyond the edge of the hanger, approximately parallel with the axis thereof, and parallel with each other at the ends of the curved body.

The described disks do not form part of the present invention.

Having thus described my invention, I claim as new, and desire to secure by Letters Patent,—

The herein-described bearing sockets, comprising semi-circular members having the ends thereof in the form of spurs integral with the body of the socket, the material being bent diagonally at the base of the spurs and then at substantially right angles at 60 points inward from the said diagonal lines, the ends of the bearings thus presenting return-bent members and members beneath the said return-bends, the spurs projecting from the last mentioned members and projecting beyond a side edge of the socket approximately parallel with each other and approximately parallel with the axis of the socket.

In testimony whereof I have signed my name to this specification in the presence of two subscribing witnesses.

JOHN EDWARD NACE.
